United States Patent Office

Des. 201,347
Patented June 15, 1965

201,347

WATER CLOSET

Gerard D. Phillips, Jr., Prospect, Ky., assignor to American Radiator & Standard Sanitary Corporation, New York, N.Y., a corporation of Delaware

Filed Sept. 28, 1964, Ser. No. 82,141

Term of patent 14 years

(Cl. D4—5)

T 1 □. 1.

T 1 □. 2.

T 1 □. 3.

Fig. 5.

Fig. 6.

Fig. 4.

FIG. 1 is a front elevational view of a water closet, showing my new design;

FIG. 2 is a top plan view thereof;

FIG. 3 is a side elevational view thereof;

FIG. 4 is a front elevational view of a modified form thereof;

FIG. 5 is a side elevational view thereof; and

FIG. 6 is a top plan view.

The side not shown of each water closet is substantially like the side shown.

The rear not shown of each form of the water closet is plain.

This application is a continuation-in-part of application Serial No. D. 70,087, filed May 11, 1962, and now abandoned.

I claim:

The ornamental design for a water closet, substantially as shown and described.
